UNITED STATES PATENT OFFICE

2,011,374

BRUSH HOLDER

Franklin H. Pritchard, Erie, Pa., assignor to
General Electric Company, a corporation of
New York

Application October 12, 1932, Serial No. 637,449

7 Claims. (Cl. 171—324)

My invention relates to brush holders for dynamo-electric machines.

In the designing of modern alternating current railway motors it has been found necessary to increase the number of poles for a given diameter of armature, and in some instances the number of poles for a given motor has been doubled. The space available for brush holders in the new design is not sufficient to accommodate the required number of brush holders of the ordinary type used in railway motor construction. For this reason it is necessary to provide a type of brush holder having the necessary brush feeding and pressure characteristics and occupying a small space.

The object of my invention is to provide a simple and compact brush holder of improved construction for dynamo-electric machines, in which substantially constant brush pressure is obtained.

For a better understanding of my invention, reference may be had to the following description taken in connection with the accompanying drawings in which Fig. 1 is a side elevation partly in section of a pair of brush holders embodying my invention mounted on a brush yoke; Fig. 2 is a perspective view of one of the brush fingers; Fig. 3 is a perspective view from the brush guide side of the right hand brush holder of Fig. 1; and Fig. 4 is a perspective view of the other side of Fig. 3 with the brush guide and pressure fingers removed.

Referring now to Fig. 1, I have shown a pair of brush holders 10 each being of the same construction except that they are made for right and left mounting, respectively. The brush holders 10 are secured to insulating studs 11 by cap-screws 12, the studs being secured to the brush yoke 13 by threaded connections 14. Each of the brush holders comprises a main body 15 and an arm or bracket 16 formed integrally therewith, and a brush guide block 17 positioned on the main body 15 by a rabbeted joint and secured thereto by capscrews 18. The construction of the brush holders can best be seen in Figs. 3 and 4, where it will be noted that each of the holders has been shown as constructed to accommodate five brushes. As shown in Fig. 1, the brush holders are provided with pressure fingers 19 actuated by compression springs 20 for urging carbon brushes 21 through the guides 17a in the block 17 into contact with a current collecting device. The brush guides are provided with openings or slots 22 in the center thereof, so that the brush pressure fingers 19 may follow the brush down through the

guide as the brush becomes worn. Compression springs 20 are located in recesses 23 in the main body of the brush support. It will be noted that this makes possible a very compact construction.

The construction and arrangement of the brush pressure fingers 19 can best be seen by referring to Figs. 1 and 2. These brush pressure fingers are made of a light construction in order that they shall have little inertia and consequently may easily follow the brush in its vibrating movement caused by irregularities in the surface of the commutator. Each brush pressure finger 19 comprises a U-shaped bracket 24 to which are secured a flat spring 25 and a conductor strip 26 spaced apart at their mid-portions, as shown, and held together at their outer ends by a contact piece 27 engaging the top of the carbon brushes 21. The conducting strip 26 is bent around the flat spring and the top of the bracket and extends over the upturned lug 24a on the bracket. A strip 28 of metal extends about the U-shaped bracket, the conducting strip 26 and the several parts are held together by the rivets 29. The current leads 30 for the brushes are secured to the upturned lug 24a by a screw 31. The U-shaped bracket 24 is provided with bosses 24b and a bearing 32 which is insulated from the bracket and the bosses by an insulated bushing 33. This insulated bushing is provided in order to prevent the passage of current between the supporting arm and the bracket 24, which would produce pitting and undesirable deterioration of the bearings. Several brush pressure fingers 19 are secured to the main body of the brush holders 10 by a pin 34 which passes through the lugs 35 formed on the main body 15 of the brush holders, insulating washers 33' being provided to insulate the ends of the bosses 24b from the lugs 35. In order to transmit the thrust of the compression spring 20 to the brush pressure finger 19 the U-shaped bracket 24 is provided with a pin 36 across the ends of the bracket. This pin engages an insulating thrust transmitting block 37 which is seated in the end of the spring 20. It will be apparent that the thrust of the spring 20 against the bracket 24 will urge the brush pressure finger 19 against the brush 21 and maintain contact between the brush and the commutator or other current collecting device with which it is employed. In this brush holder construction the pressure finger is arranged in close proximity to the brush guide and since the compression spring is located between the brush guide and the pressure finger pivot, the space is saved which is occupied.

cupied in the ordinary type of holder by spiral or helical springs extending about the finger pivot. This results in a very compact construction making possible the use of shorter supporting arms and closer grouping of the sets of brushes.

Referring to the sectional view of the brush pressure finger 19 shown on the left hand brush holder of Fig. 1, it will be noted that as the bracket 24 is rotated about the pin 34 by the compression spring 20, the effective lever arm of the spring about the pin 34 will be increased, or, in other words, the distance between the pin 34 and the line of application of the force of the spring 20 will be increased. According to my invention the brush fingers and the spring 20 are so related that this increase will be effective throughout the working range of the finger as it moves the carbon brush through the guide. Now since the force of the compression spring is decreased as it expands and since the effective lever arm about the pin 34 is increased, it will be apparent that there is a compensating effect and that the pressure on the brush will be maintained substantially constant in all positions of the finger as the brush is worn.

In the operation of my improved brush holder, therefore, as the brushes 21 are worn down the brush pressure fingers 19 will follow them and will maintain substantially constant pressure between the brush and the surface of the moving current collecting surface. At the same time, the low inertia construction of the brush pressure fingers enables them to easily follow any variations in movement due to the irregularities of the commutator when it is running at high speed which is essential to the maintenance of even distribution of current between the brushes and the avoidance of destructive arcing.

What I claim as new and desire to secure by Letters Patent of the United States, is:

1. A brush holder for dynamo-electric machines including a brush guide, a pressure finger for urging a brush through said guide, means for pivotally supporting said finger at one side of said guide, means including a compression spring arranged between said guide and said pivotal support for actuating said pressure finger, and means for preventing passage of current from said pressure finger through said pivotal support and through said compression spring.

2. A brush holder for dynamo-electric machines including a brush guide, a low inertia pressure finger for urging a brush through said guide, means for pivotally supporting said finger at one side of said guide, a compression spring arranged between said guide and said pivotal support for actuating said pressure finger, and means for preventing passage of current from said

pressure finger through said pivotal support and through said compression spring.

3. A brush holder for dynamo-electric machines including a brush guide, a pressure finger for urging a brush through said guide, means including a bracket secured to said pressure finger for pivotally supporting said finger at one side of said guide, means including a compression spring arranged between said guide and said bracket for actuating said pressure finger, and means for preventing passage of current from said pressure finger through said pivotal support and through said compression spring.

4. A brush holder for dynamo-electric machines including a brush guide, a pressure finger for urging a brush through said guide, means including a sleeve of insulating material for pivotally supporting said finger at one side of said guide, a thrust block of insulating material pivoted on said pivotal supporting means, and a compression spring engaging said thrust block and arranged between said block and said guide for actuating said pressure finger.

5. A brush holder for dynamo-electric machines including a brush guide, means including a pressure finger pivotally supported at one side of said guide for urging a brush through said guide, means for preventing passage of current from said pressure finger through the pivotal support therefor, means including a compression spring arranged between said guide and said pressure finger for actuating said pressure finger, and means including an insulating thrust block pivoted on said pressure finger and engaging said compression spring for increasing the effective lever arm of said compression spring about the pivotal support of said pressure finger as said compression spring is extended.

6. A brush pressure finger comprising a U-shaped bracket, a flat spring, a strip of metal of high electrical conductivity folded about said bracket and one end of said spring, means for securing said bracket said spring and said strip together at said one end, a brush contact piece secured to said spring and said strip near the other end of said spring, and means for connecting an electrical lead to said bracket.

7. A brush pressure finger comprising a U-shaped bracket, a flat spring and a strip of metal of high electrical conductivity secured together and to said bracket, a brush contact piece secured to said spring and said strip remote from said bracket, said spring and said strip being spaced apart between said bracket and said contact piece, and means for connecting an electrical lead to said bracket.

FRANKLIN H. PRITCHARD.
